(57) **CLAIM**

The ornamental design for a vehicle wheel, toy vehicle wheel, and/or replicas thereof, as shown and described.

DESCRIPTION

This application contains subject matter related to the following co-pending U.S. design patent application:
Application Ser. No. 29/594,702 filed Feb. 22, 2017 and entitled "Vehicle Wheel."

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front view thereof;

FIG. 5 is a rear view thereof; and,

FIG. 6 is a side view thereof.

FIG. 5 is shown in low-contrast rendering to depict environmental subject matter and forms no part of the claim.

1 Claim, 6 Drawing Sheets
